US0D1095165S

(12) **United States Design Patent** (10) **Patent No.:** **US D1,095,165 S**
(45) **Date of Patent:** **** Sep. 30, 2025**

(54) **BEVERAGE CARRIER**

(71) Applicant: **MBM Technologies, LLC**, Burr Ridge, IL (US)

(72) Inventor: **Maxwell Boston Merchant**, Burr Ridge, IL (US)

(73) Assignee: **MBM Technologies, LLC**, Burr Ridge, IL (US)

(**) Term: **15 Years**

(21) Appl. No.: **29/997,073**

(22) Filed: **Apr. 4, 2025**

Related U.S. Application Data

(62) Division of application No. 29/954,437, filed on Jul. 26, 2024, now Pat. No. Des. 1,081,283.

CLAIM

The ornamental design for a beverage carrier as shown and described.

DESCRIPTION

FIG. 1 is a top, front, right perspective view of a beverage carrier showing the new design;

FIG. 2 is a bottom, rear, left perspective view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is a top, front, right perspective view of an alternative embodiment of the beverage carrier showing the new design;

FIG. 10 is a bottom, rear, left perspective view thereof;

FIG. 11 is a front view thereof;

FIG. 12 is a rear view thereof;

FIG. 13 is a right view thereof;

FIG. 14 is a left view thereof;

FIG. 15 is a top view thereof; and,

FIG. 16 is a bottom view thereof.

The broken lines showing the remainder of the beverage carrier depict environmental structure and form no part of the claimed design.

1 Claim, 16 Drawing Sheets
